UNITED STATES PATENT OFFICE.

ANDREW R. ANDERSON, OF NORTH ARLINGTON, NEW JERSEY, ASSIGNOR OF ONE-HALF
TO JAMES H. PAUL, OF NEWARK, NEW JERSEY.

SHOE-LAST.

1,163,630.

Specification of Letters Patent. Patented Dec. 14, 1915.

Application filed July 13, 1914. Serial No. 850,792.

To all whom it may concern:

Be it known that I, ANDREW R. ANDERSON, citizen of the United States, residing at North Arlington, in the county of Hudson and State of New Jersey, have invented certain new and useful Improvements in Shoe-Lasts, of which the following is a specification.

This invention relates to shoe lasts.

10 The ordinary last is either formed in one piece, or it embodies a hinged heel section, and after the shoe has been formed upon the last and it is desired to remove the shoe it is, in the use of such a last, necessary 15 to exert considerable force in order to pull the shoe from the last and in disengaging the heel of the shoe from the last the shoe must be bent back at the instep of the shoe which is liable to result in the shoe becoming torn or otherwise marred.

It is therefore an aim of the present invention to provide a shoe last so constructed that a shoe formed thereon may be readily and quickly removed from the last when desired, the last embodying a heel section which is movable to recede from the heel of the shoe whereby to clear the heel to permit of the shoe being loosely slipped off from the body of the last.

30 Another aim of the invention is to provide a means for locking the sections comprising the last so that the last will be rigid while the shoe is being formed thereon, the means provided being adapted to not only hold 35 the sections against relative sliding movement upon each other but also to draw the sections together so that there will be no loose play.

In the accompanying drawings: Figure 1 40 is a side elevation of the last embodying the present invention in working condition. Fig. 2 is a similar view, illustrating the sections of the last relatively displaced so as to permit of the shoe formed thereon being 45 removed from the last. Fig. 3 is a detail vertical front to rear sectional view, illustrating the locking means for holding the sections of the last against relative movement. Fig. 4 is a section in a plane at right 50 angles to the plane of Fig. 3. Fig. 5 is a detail view illustrating the locking post and plate in position to permit of the last sections being relatively moved. Fig. 6 is a 55 similar view but illustrating the parts in locking position. Fig. 7 is a perspective

view of the locking plate. Fig. 8 is a perspective view of the locking post.

Corresponding and like parts are referred to in the following description and indicated in all the views of the accompanying drawings by the same reference characters.

In the drawings, the toe or body portion of the last is indicated by the numeral 1 and the heel section by the numeral 2. The body section 1 is provided with an oblique 65 or inclined rear end face 3 and the heel section 2 is provided with a correspondingly inclined forward end face 4. For the purpose of slidably connecting the sections 1 and 2 with each other and with their faces 3 and 70 4 in contact, as shown in Figs. 1 and 2, the rear end face of the section 1 is formed with a slot 5 in which is fitted a combined locking and guide plate 6, the plate being held in place by means of transverse pins 7 fitted 75 through the rear end portion of the last section and through the openings in the said plate. The plate projects through the said rear end face of the section 1 and into a slot 8 formed in the forward face of the heel 80 section 2, the projecting portion of the plate being slidably received within the said slot. The said projecting portion of the plate is formed with a longitudinally extending slot 9 and transverse pins 10 are fitted 85 through the forward portion of the heel section 2 and project through the said slot 9.

In this manner the sections 1 and 2 are connected for limited relative sliding movement but are held against separation. Referring now to Figs. 1 and 2 of the drawings, it will be apparent that due to the inclination of the contacting faces 3 and 4 of the sections 1 and 2, the sections may be 90

relatively displaced either by moving the toe section upwardly or the heel section downwardly, as shown in Fig. 2. The heel section will recede from the heel of the shoe, being formed upon the last and consequently will clear the heel of the shoe thereby permitting of the shoe being readily slipped off from the body or toe section 1. Moreover, it will be apparent that the last is in effect considerably shortened when its sections are 100 relatively displaced. In order to hold the sections in the position shown in Fig. 1 of the drawings, there is provided a locking device which will now be described.

The locking device includes a locking post which is housed and rotatable within 110

a barrel 11 fitted in an opening formed in the under side of the heel section 2, the axis of the opening being at right angles to the edge of the locking plate. The locking post is indicated by the numeral 12 and, as stated, is rotatably fitted within the barrel 11, the post near its inner end being formed with a circumscribing groove 13 and the wall of the barrel being struck in, as at 14, to form portions seating in this groove and thereby holding the post against accidental displacement within the barrel although not interfering in any way with its rotative movement. In order that the post may be rotated, it is provided at its outer end with a flattened head or bit 15 for the engagement of a suitable wrench or key for the purpose stated. The inner end of the barrel 11 terminates at the bottom of the slot 8 and the locking post 12 beyond this end of the barrel, is reduced in diameter, as indicated at 16, and has its reduced end formed with a diametrically extending notch 17 of a width slightly greater than the thickness of the projecting portion of the plate 6. The reduced portion 16 of the locking post is formed with a single thread 18, which is of course interrupted at the ends of the notch 17. The locking plate 6 is formed in the edge of its projecting portion with a notch 19, the side walls of which are formed with substantially V-shaped notches 20, so located as to receive the thread 18 when the locking post is rotated. By reference to Figs. 4, 5 and 6 of the drawings, it will be observed that in one position of the locking post, the notch 17 occupies the same position as the edge of the projecting portion of the locking plate, and in this position of the post, the sections 1 and 2 may have relative sliding movement. When it is desired, however, to lock the sections in the relative position shown in Fig. 1, the post 12 is given a quarter turn so that the notch will be disposed transversely of the line of extent of the edge of the projecting portion of the locking plate, the post, at such time, having its reduced end projecting into the notch 19. Upon such rotative movement of the post, the thread 18 will ride in the notches 20 and not only will the section 2 be held against sliding movement with respect to the section 1 of the projecting portion of the locking plate as a guide, but the section 2 will be drawn firmly against the section 1 due to the cam action of the thread 18.

From the foregoing description of the invention, it will be apparent that the sections comprising the last may be securely and firmly locked together in the relative position shown in Fig. 1 during the operation of forming the shoe of the last and that when it is desired to remove the shoe from the last, this may be readily accomplished by rotating the post 12 to the position

shown in Figs. 4 and 5 of the drawings, whereupon the sections may be relatively displaced, the section 2, in such manipulation of the sections, being caused to recede from the heel of the shoe.

Having thus described the invention, what is claimed as new is:

1. In a last, a body section, a heel section, the sections having contacting oblique faces, means slidably connecting the sections, and means for holding the sections against relative sliding movement and operable to draw the sections together at their contacting faces.

2. In a last, a body section, a heel section slidably connected therewith and movable to shorten the length of the last, and means for holding the sections against relative movement and for drawing the sections together.

3. In a last, a body section, a heel section, the said sections having contacting oblique faces, a locking plate carried by one of the sections and projecting slidably into the other section, the said plate in its projecting portion being provided with a notch, and a locking post carried by the last-mentioned section and having a portion arranged to seat within the notch, the said portion being provided with a notch to slidably receive the projecting portion of the plate in one position of the post.

4. In a last, a body section, a heel section, the said sections having contacting oblique faces, a locking plate carried by one of the sections and projecting slidably into the other section, the said plate in its projecting portion being provided with a notch, and a locking post carried by the last-mentioned section and having a portion arranged to seat within the notch, the said portion being provided with a notch to slidably receive the projecting portion of the plate in one position of the post, the walls of the notch in the plate being formed with notches and the said portion of the post being provided with a cam portion to engage in the said notches.

5. In a last, a body section, a heel section, the said sections having contacting oblique faces, a locking plate carried by one of the sections and projecting slidably into the other section, the said plate in its projecting portion being provided with a notch, and a locking post carried by the last-mentioned section and having a portion arranged to seat within the notch, the said portion being provided with a notch to slidably receive the projecting portion of the plate in one position of the post, the walls of the notch in the plate being formed with notches, and the said portion of the post being provided with a thread to engage in the said notches.

6. In a last, a body section, a heel section, the sections having oblique contacting

faces, a plate carried by one of the sections and slidably fitting within the other section and being formed with a slot, a pin secured transversely through the last-mentioned section and extending through the slot in the plate whereby to connect the sections for relative sliding movement and to limit such movement, the projecting portion of the plate being formed with a notch, and a locking post rotatably mounted in the second-mentioned section and arranged to project into the notch whereby to hold the sections

against relative sliding movement, the said portion of the post having a notch and being rotatable to position its said notch to slidably receive the projecting portion of the plate. 15

In testimony whereof I affix my signature in presence of two witnesses.

ANDREW R. ANDERSON.
